UNITED STATES PATENT OFFICE.

FRED H. PERKINS, OF BRIDGEWATER, MASSACHUSETTS, ASSIGNOR OF ONE-
THIRD TO HARRY K. PERKINS, OF BRIDGEWATER, MASSACHUSETTS.

CLOTHES-WRINGER.

SPECIFICATION forming part of Letters Patent No. 707,974, dated August 26, 1902.

Application filed July 17, 1899. Serial No. 724,028. (No model.)

To all whom it may concern:

Be it known that I, FRED H. PERKINS, of Bridgewater, in the county of Plymouth and State of Massachusetts, have invented an Improved Clothes-Wringer, of which the following is a specification, reference being had to the accompanying drawings, in which—

Figure 1 is a side elevation of a clothes-wringer embodying my improvements, and Fig. 2 an end view of the same with certain parts removed to more clearly illustrate certain features of my invention. Fig. 3 is a central longitudinal section on line 33 of Fig. 2, and Fig. 4 is a section on line 44 of Fig. 1.

My invention relates to clothes-wringers of that type which comprise in construction a lower driving-roll and an upper roll movably supported so as to permit fabrics of varying thickness to pass between said rolls, and said upper roll is usually pressed against the lower roll by means of a spring and is rotated by frictional contact with the lower roll or with the interposed fabric.

My invention relates particularly to the lower roll and the driving mechanism for said roll.

The object of my invention is to construct a clothes-wringer with a hollow lower driving-roll and to provide a compact and simple driving mechanism for said lower driving-roll, part of which is within and shielded by said hollow roll.

My invention is a clothes-wringer comprising a hollow driving-roll and driving mechanism for said roll, consisting of a shaft extending through and free to turn within said roll and operatively connected at one or both ends with the roll and means for rotating the shaft within the roll to actuate the latter.

Referring to the drawings, the lower roll A is constructed from a hollow cylinder provided with an outer covering A', of rubber, and said roll is supported by standards B B, in which it has its bearings. The standards

B are each secured to a base B', which is provided with the usual clamps B', connected thereto in the usual manner. Each standard B is constructed with an aperture b, which is larger in diameter than the outside diameter

of roll A, and within this aperture are located 50 antifriction-rolls b', grouped around said roll A and occupying the space intermediate the walls of said aperture and said roll A. The rolls b' are held in place within the standards by means of retaining-rings b², which are secured to the standards B by means of screws b³. By this construction a very nearly frictionless bearing is provided for the roll A, and the power required to rotate said roll when the wringer is in use is much less than 55 has heretofore been necessary. The driving mechanism for roll A consists of a shaft C, extending through and free to turn within the hollow roll A and journaled in brackets c' c', projecting upwardly from base B'. One 60 end of shaft C projects slightly beyond its bracket c' and has secured to it a crank-handle c², by means of which said shaft is operated. Mounted on shaft C are two pinions c³ c⁴, which are fixed thereto by means of set-screws c⁴ or otherwise, and said pinions are each located near one end of shaft C and engage internal gears c⁵, the hubs c⁶ of which are internally screw-threaded and screwed upon the externally-screw-threaded ends of 70 the roll A. By this arrangement and construction a convenient and compact driving mechanism is provided, the rotating gears of which are inclosed, thereby preventing their accidental engagement with fabrics being operated upon by the wringer.

Other features of construction shown in the drawings relating to the upper roll D are old and well known, and detailed description of them is not necessary.

What I claim as my invention is—

The improved clothes-wringer above described comprising wringer-rolls, one of which has a tubular shaft; a power-driven shaft inside the tubular shaft; and pinions on the power-shaft meshing with internal gears on the tubular shaft whereby the clothes passing between the wringer-rolls are not exposed to the teeth of the gearing.

FRED H. PERKINS.
